WILLIAM GENTRY SHELTON, OF ST. LOUIS, MISSOURI

HAIR CURLING APPARATUS AND METHOD

Application filed June 26, 1931. Serial No. 547,103.

This invention relates to hair curling and consists in novel hair holding and enclosing devices and the method of using the same.

One object of the invention is to provide a device for curling or straightening the hair which combines a hair clamp and curling rod in a single member and which may be more conveniently handled than devices heretofore in use.

10 Another object is to provide a novel supply element which will closely envelope the hair and which will remain in position on the hair strand when tightly wound about the curling rod without the application of 15 any outer clamping member such as is generally used and may be eliminated by the use of the present invention.

These and other objects are attained in the structure illustrated in the accompanying 20 drawing in which—

Figure 1 is a perspective view of the supply member.

Figures 2 and 3 are detail views showing the method of applying the supply to a hair 25 strand.

Figure 4 is a side view of the device with a supply encased hair strand applied thereto.

Figure 5 is a side view of a modified form of the device.

30 Figure 6 is a similar view of another form.

Figure 7 shows a device similar to that in Figure 5, but being used in straightening the hair.

Figure 8 is a plan view of the protector 35 clamp and showing the curling rod in section.

The hair mounting device comprises an elongated rod 1 which has oppositely disposed prongs 2 projecting therefrom at regular intervals in staggered relation to each other. A heating element 15 extends interiorly of rod 1 and merges at the outer end with a socket 16 having prongs 17 for engagement with a current connection 18.

45 Secured to the other end of the rod is a rod mounting and a scalp protector in the form of a clamp including jaws 3 and 4 which are composed of body portions 5 and 6 having felt pads 7 and 8 on the undersides and metal strips 9 and 10 on top. The jaws are

pivoted together at one end by means of a link 11 riveted to strips 9 and 11, respectively, and at the other end are provided with locking means including a double link 12 pivoted on strip 9, and a cam lever 13. Double link 12 is adapted to fit over the end of strip 10, the strip having a recessed corner 14 for receiving the locking cam 13a.

Figure 1 illustrates the novel tubular supply covering 19 made of absorbent material 60 and which is particularly adapted for use in connection with the novel curling device shown in Figure 4, as well as the modified forms to be described hereafter.

In operation of the device shown in Figure 4, a segregated strand of hair S is first gripped between the clamping jaws 5 and 6. The moistened supply 19 is then applied to the strand by means of a hook 20 which is inserted through the tube and engaged with the strand as shown in Figure 2, and then both are withdrawn, as illustrated in Figure 3, causing the hair to be drawn through the tube. The encased strand is wound upon the rod and projecting prongs 2 in the manner illustrated in Figure 4 and secured at its end to the rod by a cord 21. The device may then be connected with a source of current causing heat to be generated within the rod for setting the curl.

Figure 5 shows a straight rod 22 mounted on a scalp protector clamp indicated generally at 23 and similar to the clamp shown in Figure 4. This form is adapted for making cork screw or standard curls. In operation of this modification, the hair strand is gripped between the jaws of the clamp and encased in the tubular supply member 24 in the manner previously described, and then helically wound about the rod and secured thereto by a cord 25. Heat is applied by means of a suitable cylindrical heater 37, of well known form, into which the rod and wound strand may be inserted.

Figure 6 illustrates another modification in which a plate-like body member 28 has a boss 36 at one end which is rigidly secured to the upper surface of one of the jaws of protector clamp 27. Pegs 29 project outwardly from member 28 at intervals for receiving the con-

volutions of the hair strand. A heating element 26 extends longitudinally of member 28 and has a socket 30 at its outer end for attachment with a source of electricity. In this 5 form of the invention, the supply encased strand is wound back and forth around alternate pegs forming a series of U's which are disposed substantially in a common plane forming the croquignole type wave.

10 The device shown in Figure 5 may also be used as a hair straightener, as illustrated in Figure 7. In the straightening operation the hair strand is gripped between the jaws of clamping member 32, tubular supply member 33 is applied, and the encased strand is stretched along the rod 34 in a position paralleling the same and its end is secured to the rod by a cord 35. Heat may be applied by means of a hollow cylindrical heater similar 15 to that indicated at 37 in Figure 5.

In all of the forms described the rigid attachment of the protector clamp with the elongated curling member is particularly advantageous in relieving the customer of an 20 annoyance of hair pulling. In the straightening operation, particularly, this arrangement causes the pull on the hair to be received and counteracted within the curling member alone with the result that no forces are applied to the portion of the hair strand 25 beneath the clamp. The cylindrical supply member is preferably made of continuous pliable material, such as cotton or linen fabric, which permits the strand to be more closely and permanently 30 enveloped than is the case with similar articles previously used for the same purpose. Moreover, the uniform thickness of the material and the cylindrical shape of the member 35 enable the operator to more readily form the strands into smooth curls than has heretofore been possible and eliminates the possibility of portions of the hair being exposed due 40 to twisting of the supply covering. This feature of the tubular supply covering is of particular 45 advantage where the hair is wound in helical form as distinguished from plane spiral form and also where the hair is distorted in different planes as illustrated in 50 Figure 4.

No outer member other than the tubular supply covering is used with the devices in Figures 4 and 6. This form may also be used in marcel waving in which case the supply member is eliminated and heat is applied for a shorter time than is necessary in permanent 55 waving.

The curling rod preferably is permanently secured to one of the clamping jaws, as by 60 soldering, although other securing means may be used, if desired, which would permit disassembling of the parts. The exact spacing of the prongs in Figure 4, and of the pegs in Figure 6, is not essential although it is desirable that they be positioned uniformly.

Any suitable form of protector clamp and curling rod might be used in the broadest phase of the invention.

Obviously these and other modifications might be made without departing from the 70 spirit of the invention and I contemplate the exclusive use of all such variations as come within the scope of my claims.

What is claimed is—

1. A supply member for applying moisture 75 to a strand of hair in a waving or straightening operation and consisting of a cylindrical tube of pliable absorbent material adapted to receive and closely encase the strand of hair without opening irrespective of distortion thereof.

2. In permanent waving apparatus, a substantially cylindrical supply member for application to a pencil strand of hair, and a curling member for winding said strand and 80 supply member and comprising an elongated element and prongs projecting sidewardly therefrom at intervals, said supply member being adapted to closely encase said strand when distorted around said prongs.

3. In hair straightening apparatus, a clamp member for gripping a strand of hair, an elongated member projecting therefrom, a sleeve-like supply covering for encasing the strand, and means for attaching said strand and supply to said elongated member in a position substantially paralleling the same.

4. The method of waving hair which consists in applying near the base of the strand a protector clamp having a curling member extending therefrom and provided with prongs projecting sidewardly therefrom, enclosing the strand in a cylindrical supply member, winding the strand successively around said prongs to form a series of U- 100 shapes, stretching the strand by securing the outer end near the outer end of said member, and applying heat to the interior of the wound strand.

5. The method of waving a strand of hair 105 which consists in inserting the straight strand into a moistened hollow supply covering, winding the strand and covering about a curling member, and applying heat to said member for setting the curls.

6. In hair curling apparatus, a sleeve-like absorbent covering for encasing a hair strand, a curling rod for winding the encased strand, and a hair clamp secured to the end of said rod.

In testimony whereof I hereunto affix my signature this 23rd day of June, 1931.

WILLIAM GENTRY SHELTON.
